HARRY W. RIES, OF COLLINGSWOOD, NEW JERSEY, AND LANDY B. BROWN, OF PHILADELPHIA, PENNSYLVANIA.

TENNIS-RACKET.

1,132,214.

Specification of Letters Patent. Patented Mar. 16, 1915.

Application filed October 16, 1914. Serial No. 866,398.

To all whom it may concern:

Be it known that we, HARRY W. RIES, a citizen of the United States, and resident of Collingswood, county of Camden, and State 5 of New Jersey, and LANDY B. BROWN, a citizen of the United States, and resident of Philadelphia, county of Philadelphia, State of Pennsylvania, have invented an Improvement in Tennis-Rackets, of which the following is a specification.

This invention relates to tennis rackets and more particularly to the manner of stringing the racket.

It has for an object to provide a tennis 15 racket having a playing area of relatively high resilience which is so positioned and arranged as to receive the greatest amount of use, and bounding said area by other areas of relatively less resilience.

It has for a further object to provide a tennis racket wherein the frame is braced by reason of the arrangement of the strings to prevent its distortion in case one or more of the strings are broken; also to permit of 25 easy repair.

It has also a further object, namely, to provide a tennis racket strung in such a manner that better control of the ball is obtained.

Our invention comprehends features of construction which will be better understood by reference to the drawings, in which:

Figure 1 represents a side elevation of a 35 tennis racket embodying our invention; Fig. 2 represents diagrammatically the arrangement of the strings; and Fig. 3 represents a section of a modified form of stringing, said section being taken at a point corresponding to the line 3—3 of Fig. 1.

1 designates the annular frame of a tennis racket, which is suitably bored, as shown at 2 for example, for the purpose of forming transverse openings for looping the strings 45 through the frame in the proper manner to form a playing area with the strings in the same plane. In the present instance we have formed a playing area of two grades of strings, 3 and 4, the former being of relatively fine gut while the latter is of coarser or heavier gut. It will be noted, however, 50 that we do not wish to be limited to this

particular grade construction of string, since obviously the strings 4 may be of the same grade or degree of fineness as the 55 strings 3 but doubled as shown at Fig. 3 so that each string as it crosses the playing area comprises two strands. In using the term "gut" it will be understood we do so in the broad sense and do not wish to be 60 limited necessarily to actual "gut" as the only material of which the strings may be made, as obviously any material may be employed which gives strength, resiliency and durability for the purpose intended, and are 65 included under the term "gut" as employed in this specification and claims.

The preferred manner of stringing the racket consists in looping the string 3 through the frame and across the opening 70 provided therein in such a manner as to form a main playing area which is bounded by areas formed by the string or strings 4. Thus the string 3, in the preferred construction, passes through the frame 1 as 75 many times as required to form a playing field of suitable dimensions and is preferably passed longitudinally and transversely of the frame as shown in Fig. 1, though our invention is not limited to this particular manner of traversing the opening in the racket since the particular direction of the crossed strings relative to the frame 1 is immaterial so long as the proper playing area is provided. The result of thus stringing 80 the racket with the string 3 is to form intersecting, longitudinal and transverse portions interwoven and forming an area 85 of great resilience and which area is preferably located where the field of play is the 90 greatest.

The strings 4 are utilized as a means for bracing the racket frame for assisting in maintaining it at all times and under all conditions accurate as to shape and also extending the playing area; and in attaining this end, we have passed one of the strings 4 longitudinally of the racket and at one side of the field of the string 3, suitably looping the string 4 through the frame and 95 then passing it at right angles to its former course and carrying it transversely of the frame, also to one side of the playing field 100 of the string 3. The other string 4 is cor-

respondingly looped through the frame 1 and transversely and longitudinally thereof as shown in Fig. 2 and has its respective portions intersecting the other string 4. By reference to Fig. 2 it will therefore be apparent that the strings 4 form areas 6 respectively positioned adjacent the corners of the area 5 and also form areas 7 at the sides of the area 5, these latter areas, however, 10 being partially formed by the string 3.

From the foregoing, it will be seen that the playing area 5 of the racket is formed of resilient flexible gut comprising the crossed or interwoven portions of string 3 and is 15 separate and distinct from the areas in which the strings 4 form a part or whole. The advantage of this construction will be readily apparent in view of the fact that the greater portion of play takes place upon the area 5 20 formed by the string 3 of relatively fine gut and in case the string forming the said area 5 should break there is no objectionable loosening of the tension upon the racket frame, since the strings 4 hold the frame 25 firmly in its normal shape. While the strings 4, therefore, primarily serve as a means to prevent the frame from becoming distorted, especially during repairs to the strings 3, they also, by reason of being 30 preferably heavier or thicker gut, serve to give an added control to the ball either in serving or in returning it. Such stringing as here described is particularly useful in giving a more pronounced cut to the ball.

35 In Fig. 3 we have illustrated a modification wherein the strings 4 may be of fine gut and doubled in number by looping through the apertures in the frame so that double the number of strands cross the opening or 40 face of the racket in the same areas 6 and 7, heretofore described, as occupied by the strings 4, said strands being preferably strung through apertures 2 in the frame in pairs. By employing more strands (closer 45 together) in a given area, it is manifest that greater rigidity or less resiliency is imparted to such areas than in the area 5 and the broad results of our invention will be secured.

50 The area 5, bounded laterally on each side by the less resiliency areas 6 and 7 formed by the longitudinal strands 4 or their equivalent of less resiliency, fulfills the more important functions of our invention, and 55 therefore we may omit the transverse stringing to give the less resiliency areas if so desired.

In connection with the use of the strings 4 it will be understood that we do not wish 60 to be limited to the number of these strings forming the several areas, as obviously this feature may be varied to suit conditions and still be within the scope of our invention.

It will be apparent that a racket strung in 65 accordance with our invention may be re-

paired very easily and economically since the strings 4, or double strings as substitutes therefor, serve to maintain the frame in its correct shape, thereby making it a simple matter to replace the string 3 forming the area 5 which receives the greatest wear. Furthermore, the strings 4 give greater control of the ball when the racket is in play as before pointed out.

The playing area of relatively high resiliency and bounding areas of relatively lower resiliency may be produced by strings of various kinds, densities, tensions, sizes or cross sectional areas (single or plural strings) and we therefore do not restrict 70 ourselves to strings of different cross sectional areas.

We do not limit ourselves to any number of string sections, but have shown three, by way of example, to provide a relatively few 75 terminal ends; and while we have described our invention in its preferred form we do not confine ourselves to the minor details as these may be modified without departing from the spirit of the invention.

Having now described our invention, what we claim as new and desire to secure by Letters Patent is:-

1. In a tennis racket, the combination of 90 an annular frame having its opening strung with crossing strings providing a central playing area formed of strings of high resiliency and the extension of said strings with strings of lower resiliency bounding 95 said central playing area, to form areas having less resiliency than the central area.

2. In a tennis racket, the combination of 100 a suitable frame, a net strung in said frame, the strings thereof arranged transversely and longitudinally to form mesh of substantially equal size and in which the central area of the strung surface has greater resiliency than the bounding area between it and the frame.

3. In a tennis racket, the combination of 110 an annular frame having its opening strung with crossing strings of substantially uniform mesh arranged to form a central rectangular area 5 of high resiliency, having 115 its sides bounded by four areas 7 of medium and lower resiliency, and four additional areas 6 of lowest resiliency connecting the areas 7 and also acting as a support to the central area of high resiliency, the construction providing means of graduating 120 the strain of impact upon the strung areas and forming a natural central pocket when said central area is struck by the ball.

4. In a tennis racket, an annular frame, 125 strands of relatively fine gut strung laterally and longitudinally across the middle of the opening of said frame a plurality of times to form an interwoven central playing area of substantially uniform mesh and relatively high resiliency, and additional 130

strands of relatively coarser gut strung laterally and longitudinally of said frame a plurality of times and meshing with the finer gut strings around the central playing area to form an interwoven area of relatively lower resiliency bounding said playing area.

In testimony of which invention, we hereunto set our hands.
